UNITED STATES PATENT OFFICE

MAJOR H. E. BECKLEY, OF SAN FRANCISCO, CALIFORNIA, ASSIGNOR TO A. J. NYSTROM
AND COMPANY, A CORPORATION OF ILLINOIS

MAP HOLDER

Application filed August 27, 1926. Serial No. 132,029.

My invention relates to map holders and particularly to map holders of the spring roller type.

One of the objects of my invention is to provide a simple, practical and inexpensive device of the class specified.

Another object of my invention is to provide means for the removal of one or more of the maps and their use elsewhere.

Another object of my invention is to provide locking means for preventing the use and also the removal of the maps.

These and other objects and advantages will be apparent from the following descriptions and the accompanying drawings, in which

Fig. 1 is a front view of an embodiment of the invention,

Figs. 2, 3 and 4 are sectional views taken along lines 2—2, 3—3, and 4—4 of Fig. 1, respectively, and

Fig. 5 is a view of the holder taken along line 2—2.

Referring more particularly to the drawings I show a map holder having a back 1, top 2, bottom 3, and ends 4. Ends 4 provide mounting means for rollers 5 on which are rolled maps 6 provided with stop rods 7 and draw rings 8. Rollers 5 rotate on pivots 9

30 mounted in apertures in end member 10, grooves 11 being formed in member 10 for aid in locating the apertures when inserting maps. The ratchet ends of rollers 5 are mounted in recesses 12 of slots 13 in end member 14. To permit and prevent insertion and removal of maps a sliding member

35 15 is provided within end member 14 and has a handle 16. Slide 15 is limited in its movement by a screw 17 projecting through a slot

40 18 in slide 15. Slide 15 is also provided with slots 19 which when put in conjunction with slots 13 of member 14 permit the ratchet end of the maps to be inserted in recesses 12 or removed therefrom. Thus in order to put

45 in or take out a map with its roller, slide 15 must be lifted and a safe and secure holding means is thereby provided. The slide 15 may if desired have a suitable locking arrangement for preventing unauthorized removal of the maps.

My invention further incorporates a feature whereby a map may be removed and used at a distant place, the spring roller being still operable. To accomplish this result I show an auxiliary holder 20 having end members 21 through which the pivot 9 and the ratchet end of the roller project and by which they are supported. End members 21 are extended to form stops for the stop rod 7 when the map and auxiliary holder are used apart from the main holder. The auxiliary holder 20 with its map is removable in the same way as described above for a single map and can be hung up independently of the main holder the spring roller still being available.

It being understood that the roller being of the usual design, containing a spring, has a ratchet device attached thereto for co-operating with a rectangular projection at one end of the roller. This rectangular projection is inserted in a notch in the end member 21 of the auxiliary frame so that when this frame and the map holder are removed from the holder the spring can be utilized for winding up the map on the roller in the same way as when in the holder.

The slide 15 will thus operate to lock the roller and the auxiliary holder in the frame in the same way as the roller mounted in the frame; that is, by closing the notches 12.

I also show means for locking the maps against unauthorized use. This comprises a rod member 22 having a scroll head 23 and an eye 24 and extending through apertures in top 2 and bottom 3 just in front of stop rods 7 when in closed position. A suitable lock can be used in eye 24, and when not in use the rod 22 can be lifted up and out of the holder.

Thus a simple and practical map holding device is provided and one permitting great diversity in use and application.

It will be understood that changes and modifications may be made without departing from the spirit of the invention.

What I claim is:

1. A device of the class specified having a supporting member provided with a bayonet slot for receiving the ratchet end of the spring roller, and means for closing the open portion of said slot to prevent the removal of

said ratchet end, said closing means comprising a sliding member and a notch in said sliding member arranged to pass over a portion of said bayonet slot.

- 5 2. A device of the class specified having a member provided with a bayonet slot for receiving the ratchet end of a spring roller and also having a slide adapted to open and close the open end of said slot, said slide having an opening to register with the said bayonet slot and arranged to be brought into registration therewith.
- 10 3. A device of the class specified comprising a member having a plurality of slots for receiving the ends of a plurality of spring rollers, and a slideable member for controlling the ends of said slots to lock said rollers in position or to permit the removal of any one or more of the same.
- 15 20 4. A device of the class specified comprising a member provided with a plurality of bayonet slots and a slide having means for controlling the open ends of said slots, said member having a plurality of slot closing devices with spaces between them to register with the slots of said first mentioned member.
- 25 5. In a device of the class specified, a roller frame, a roller therein, each end of the roller projecting beyond the said roller frame; supporting means for said roller; the said projecting ends of the roller arranged to be engaged by the said supporting means to support the said roller.
- 30 6. In a device of the class specified, a roller frame, a roller therein, each end of the roller projecting beyond the said roller frame; supporting means for said roller; the said projecting ends of the roller arranged to be engaged by the said supporting means to support the said roller and the frame, or the roller alone without the frame thereon.
- 35 7. In a map-holder including a cabinet arranged for containing and holding a plurality of map-rollers, means for mounting said rollers in said holder, said means including a member provided with a plurality of bayonet slots and a slide having registerable openings for controlling the open ends of said bayonet slots.
- 40 50 59. In witness whereof, I hereunto subscribe my name this 6th day of July, A. D. 1926.
MAJOR H. E. BECKLEY.
